UNITED STATES PATENT OFFICE.

HENRY J. HORWICH AND EDMUND A. STEINMAN, OF CHICAGO, ILLINOIS.

BEDSTEAD LOCK.

Application filed June 7, 1920, Serial No. 386,967. Renewed December 26, 1922.

To all whom it may concern:

Be it known that we, HENRY J. HORWICH and EDMUND A. STEINMAN, both residing at Chicago, Cook County, Illinois, and both 5 citizens of the United States, have invented certain new and useful Improvements in a Bedstead Lock; and we do hereby declare the following to be a full, clear, and exact 10 description of the invention, such as will enable others skilled in the art to which it appertains to make and use the same.

Our invention relates to metal bedsteads and in its general objects includes the providing of simple means constructed chiefly 15 of sheet metal for affording the operative connections between various parts of the bedstead at the corner posts.

In one aspect, our invention aims to provide a socket constructed chiefly of sheet 20 metal and adapted to be secured to a tubular bed post without employing screws or bolts, to provide a socket of this class which will permit the end rail of the bedstead to be attached directly to the same, and to 25 use the sockets at the same end portion of a bedstead as means for connecting a stiffener to this end portion. It also aims to provide strong and inexpensive sheet metal rail ends arranged for interlocking with 30 these sockets; to arrange the interlocking so that it will be augmented by the action of gravity and so that the extent of the interlocking will be controlled by the engagement of each said end piece with the adjacent 35 socket, and to allow the parts automatically to interlock to an increased extent in making up for wear on the parts. Furthermore, our invention aims to provide simple means for preventing the thrust 40 of such a rail end piece against a bedpost or a socket mounted on the bedpost from spreading the parts of the end piece out of their normal relation to each other.

In another aspect, our invention aims to 45 provide a combined side rail and spring construction in which the side rails are slidably inserted into collars or end pieces affording the operative connections both to 50 sockets on the bedpost and to the bars between which the spring or bed-bottom is stretched, to provide shoulders upon these 55 end pieces engaging the side rails to limit the tilting of the end pieces by the tension of the spring or bed-bottom, and to provide cheaply constructed but effective means upon the end pieces for limiting the insertion of

the end rails into the same. Furthermore, our invention aims to provide simple means for preventing a rotation of non-cylindrical side rails when used with such end pieces 60 and to provide an unusually rigid, neat and cheaply manufactured end piece construction. So also, our invention aims to provide an end piece construction which will readily permit the attaching of the same to the bars 65 between which the bed-bottom is stretched, and desirably to provide this attachment to the bars through part of the means which prevent the end piece from spreading. Still further and also more detailed objects will 70 appear from the following specification and from the accompanying drawings, in which

Fig. 1 is a somewhat diagrammatic elevation showing a side view of portions of a bedstead and illustrating the manner in 75 which the tension of the bed-bottom holds the end pieces upon a side rail of the bedstead.

Fig. 2 is an enlarged and fragmentary vertical section through a bed post and the 80 adjacent parts, taken centrally of both the post and the side rail of the bedstead.

Fig. 3 is a horizontal section through the same parts, taken along the correspondingly numbered line in Fig. 2. 85

Fig. 4 is a vertical section taken along the correspondingly numbered line in Fig. 1, with the spring or bed bottom parts omitted.

Fig. 5 is a perspective view of the rail end or connecting member of the previous 90 figures, together with a portion of the elliptically sectioned side rail associated therewith.

Fig. 6 is a perspective view of a simplified form of the supporting member or socket 95 carried by the bedpost and used in connection with the connecting members of Fig. 5.

Fig. 7 is a view (on a reduced scale) of the sheet metal blank from which the main part of the socket of Fig. 6 is formed. 100

Fig. 8 shows the sheet metal blank from which the connecting member of Fig. 5 was formed.

In accomplishing the purposes of our invention after the manner illustrated in the 105 drawings, we first secure to each post of the bedstead a socket member including a transverse pin freely spaced from the post, then mount a hook member upon the adjacent end of the side rail of the bedstead 110 and interlock the hooks of this member with the transverse pin on the socket member.

Both of these members are preferably constructed of steel and preferably designed so that they can be manufactured chiefly by punch press operations, thereby reducing their cost and insuring uniformity of the parts.

To use our invention in connection with bedsteads having tubular corner posts such as the hollow cylindrical posts of the drawings, we first punch an aperture 1 in each of the posts along the inner face of the post, namely the face directed towards the side rail of the bedstead. Then we provide a corresponding aperture 3 in the back 4 of the socket, which back is curved to snugly fit the post 2 and which back has a pair of webs 6 extending from its opposite edges and disposed in vertical planes. These webs are preferably parallel to each other and jointly carry a horizontal pin 5 extending transversely of the webs. The socket, as thus constructed of a single and forked metal plate and a pin or cross-bar, is held against the post of the bedstead with the perforations 1 and 3 in alignment with each other, after which I insert the bent shank 7 of a sheet metal key through these aligned perforations into the bore of the post 2 and lock this key in position by means of a wedge 8 after the manner shown in Fig. 3. This wedge tends to draw the bent shank of the key further into the post, thereby drawing the enlarged heads 9 of the key against the outer face of the back 4 of the socket so as to secure this socket firmly to the post with the cross-bar 5 in a fixed position predetermined by the location of the perforation 1 in the post. Thus arranged, each of the said sockets 35 forms a supporting member projecting inwardly of the bedstead from the post carrying that socket and each socket presents its cross-bar in a convenient position for receiving a suitable downwardly directed hook formation on the adjacent end of a side rail of the bedstead. Where this rail is to be independent of the bed spring, we desirably provide the needed hooking formation in a tube arranged after the manner disclosed in our co-pending application #386,968 on a bedstead lock and stiffener, as filed by us on June 7, 1920.

If the side rails of the bedstead are also to form a permanently connected part of the frame for the spring or bed-bottom after the manner which has become customary in recent years, we first assemble these side rails 13 in connection with the bed-bottom 14 and the connecting pieces or hook members 15, as for example after the manner shown in Fig. 1. This figure shows the ends of the side rails 13 as slipped respectively into the hook members 15, the pair of end pieces intended for each end 60 of the bedstead being connected to each

other by an angle bar 16. Then the bed bottom 14 is stretched between the two angle bars 16 and is continually tensioned by springs 17. With the parts thus arranged and with suitable stop formations 70 in the collars or hook members 15 for preventing the end rails 13 from sliding entirely through the same, it will be obvious from Fig. 1 that the tension of the springs 17 will hold the hook members or end pieces 75 15 on the side rails, so that no other fastenings will be required to retain the various parts in proper relation to each other when the resulting metal-framed bed bottom member is detached from the ends of 80 the bedstead.

As a desirable construction for such a hook member or end piece, we desirably form the latter of sheet metal with a substantially U-shaped transverse section 85 affording a rounded bottom for the elliptical side rail 13, after the manner shown in the drawings, by starting from a blank shaped as in Fig. 8. Then we bend end flaps 18 from the two shanks of the U-sectioned end piece towards each other and butt weld the tips of these shanks to each other. We also desirably connect the free ends of the U-shaped metal piece to each other by means of a strap 19 which is here 90 shown as U-shaped and as riveted to the shanks of this hook member. This strap 19 has a central perforation 30 for receiving a bolt 31 by means of which the strap is bolted to the vertical web of the angle 100 bar 16 to which the resilient bed-bottom is attached (after the manner of Figs. 2 and 4) the central portion of the strap 19 is flush with vertical shoulders 32 on the metal sides 22 of the hook member, so that 105 the strain due to the tensioning of the bed-bottom is received by these shoulders and not by the rivets 20.

To prevent the side rail 13 from sliding entirely through the bore of the end piece, 110 we arch one end of the latter upward into a riser formation 21 somewhat after the manner shown in Figs. 2 and 5. Then we provide each of the sides or shanks 22 of the U-sectioned hook member with slots 23 115 extending from the same end of this member as the riser projection 21, these slots being desirably curved upwardly so as to leave pointed prongs 24. The slots 22 are aligned with each other transversely of the bedstead, and each of these slots has its upper end oblique to the vertical extreme end of the shank 22 entered by the slot and spaced from the said end by a distance greater than the spacing of the pin 5 from 120 the back 4 of the adjacent socket member. With the slots thus formed, it will be evident from Fig. 2 that the hooks 24 of the hook member or end piece will be wedged between the pin 5 and the back 4 of the 125 130

socket member. Gravity will continuously tend to increase the firmness of this interlocking and the slope of the upper slot portions together with their extending beyond the pin 5 will permit the hooks to compensate for any wear on these parts; so that our bedstead lock enables us to combine cheapness, firmness and durability.

However, while we have heretofore described our invention in a desirable embodiment adapted for use with bedsteads having round posts and elliptical side rails, we do not wish to be limited to the details of the construction and arrangement thus disclosed. Obviously, various additions, omissions and other changes might be made without departing from the spirit of our invention or from the appended claims.

I claim as our invention:

20 1. In a bedstead, a post, a socket having a cross pin supported by the post, a U-shaped member having the front of its sides formed with hooks engaging the pin and having the rear of its sides formed with flaps which 25 extend toward each other in the same plane and have their edges abutting, a side rail seated in the bottom of said member, a U-shaped strap connecting the sides of the member, and a bed bottom having an angle 30 bar the vertical web of which latter is bolted to said strap at a point between the sides of said member.

2. In a bedstead, a post, a socket having a cross-pin supported by the post, a side rail supporting member of U-form having the front of its sides formed with hooks engaging the pin and having the rear of its sides formed with flaps which extend toward each other in the same plane and have vertical edges that abut and having curved 40

edges below the vertical edges which conformably engage the side rail, and a strap secured to the sides of the member above said vertical abutting edges thereof.

3. In a bedstead, a post, a socket having a back attached to the post and having a cross-pin, a U-shaped rail supporting member having a slot across its bottom and having the material between the slot and the front end of the member arched upwardly, 45 to form a combined double-ended stop and reinforcement of concavo-convex cross-section, the front end of the member being formed with hooks engaged over the cross pin, the hooks having vertical edges abutting 50 the inner face of the back and said arched part having its front arranged to abut the said inner face of the back and its rear to engage the rail.

4. In a bedstead, a post, a socket having a cross-pin supported by the post, a side rail supporting member of U-form having the front of its sides formed with hooks engaging the pin and having the rear of its sides formed with flaps which extend toward each 55 other in the same plane and having vertical edges that abut and having curved edges below the vertical edges which conformably engage the side rail, the bottom of said member having a slot across same and having the 60 material between the slot and the front end of the member arched upwardly to form a combined double-ended stop and reinforcement of concavo-convex cross-section, and a member connecting the sides above the vertical abutting edges thereof. 65

Signed at Chicago, Illinois, June 4th, 1920

HENRY J. HORWICH.
EDMUND A. STEINMAN.
